UNITED STATES PATENT OFFICE.

CARROLL H. CASE, OF ST. LOUIS COUNTY, AND WILLIAM C. FARRAR, OF ST. LOUIS,
MISSOURI.

BOOSTER FOR SIPHONS.

Application filed May 12, 1921. Serial No. 468,981.

To all whom it may concern:

Be it known that we, CARROLL H. CASE, a citizen of the United States, residing in the county of St. Louis and State of Missouri, and WILLIAM C. FARRAR, a citizen of the United States, residing in the city of St. Louis and State of Missouri, have invented a new and useful Improvement in Boosters for Siphons, of which the following is a full, clear, and exact specification, reference being had to the accompanying drawings, which form a part thereof.

Our invention relates to boosters to augment the flow of liquid through siphons and more particularly to boosters for siphons used in lifting water over a levee or similar elevation where the difference in level of water at the intake end of the siphon and at the discharge end thereof is small.

20 Heretofore in operating a siphon under conditions where there is a small difference in head the efficiency of the siphon is so greatly impaired that such operation is virtually ineffectual.

25 The objects of our invention are to provide means whereby the efficiency of siphons operating under such conditions will be greatly increased; to provide means for maintaining a flow of liquid through the discharge end of the siphon whereby the flow of liquid through said siphon will be augmented; and to provide a booster which will not only increase the flow of liquid through a siphon operating under a small 30 difference of head, but which will increase the volume of liquid passing through the siphon at all times under any conditions.

Our invention is clearly shown in the accompanying drawing where similar letters 40 are used to designate similar parts. The figure in the drawing shows a siphon laid over an embankment such as a levee, or any similar elevation.

45 Referring to the letters, A is a siphon laid over the levee B. The intake end C of the said siphon being positioned in the sump D from which the water is to be siphoned. The discharge end E of the siphon is arranged with the check valve F which is 50 preferably positioned away from the vertical, as shown, so that its own weight will hold it against the mouth of the discharge end E, thereby allowing the discharge of water but preventing the inflow of water or 55 air at said discharge end. The check valve

F may be raised by the cord G, or any other means. At the highest point, preferably, in the siphon A is connected the air pump H whereby the air is drawn from said siphon thereby creating a vacuum whereby 60 the siphon may be primed and may at all times be kept free of air. I is an auxiliary water pipe through which water under pressure is supplied by the force pump K to the ejector nozzle J which is arranged in 65 the discharge leg of the siphon, preferably near the end thereof, so as to augment the flow of water therethrough. Water for the auxiliary pipe I may be drawn through the pipe L by the pump K from the sump or 70 any suitable source of supply.

The operation of the siphon and the nozzle is as follows: The check valve F is held by its own weight against the discharge end E thereby preventing the inflow of air, and 75 air is drawn from the siphon by the air pump H until a vacuum is created in said siphon strong enough to suck water in at the intake mouth C and up to and past the highest point of the siphon A. The flow of 80 water down from the highest point of the siphon to the discharge end then starts and the siphon soon fills and then operates. As soon as the flow of water through the siphon commences the check valve F is forced up- 85 wardly by the pressure of the water or it may be lifted and held in an upwardly position by the cord G as described. The pump H is operated to draw water through the tube L and force it through the auxiliary 90 pipe I into the siphon A through the ejector nozzle J. The impact due to the flow of water through the ejector nozzle J tends to augment the flow of water through the discharge end E, thereby assuring a continued 95 functioning of the siphon even though the difference of head is small. The air pump H is, preferably, continued in operation to maintain the siphon free from air.

Successful and efficient operation of a 100 siphon necessitates the maintenance of the flow of liquid through the discharge leg of the siphon, and the flow through the discharge leg creates a suction in the siphon whereby the inflow of liquid at the intake 105 end of said siphon is maintained. The suction created by the outflow of liquid through the discharge leg of the siphon must be strong enough to overcome the friction in the siphon, and therefore there must be a 110

- difference of level between that of the water in the sump and that at the discharge end sufficient to overcome the friction and create a flow of water. In siphons operating under a small difference of head, the difference is often too small to maintain the suction required for successful practical operation. Our invention provides for the maintenance of a flow of liquid in the discharge leg of the siphon which is at all times much greater than the flow due solely to the difference of the levels of water in the sump and in the river thereby assuring successful operation at all times.
- 15 The air pump H and the water pump K are shown diagrammatically since we do not wish to restrict ourselves to any particular type of either.
- 20 What we claim as new and desire to secure by Letters Patent, is:
1. In combination with a siphon having a source of supply and place of discharge, means whereby said siphon may be primed, and means whereby there may be maintained through the discharge end of said siphon a flow of water from the source of supply independent of the flow through the inlet thereof.
  2. In combination with a siphon having a source of supply and place of discharge, an air pump whereby said siphon may be primed and maintained free of air, and means whereby water from said source of supply may be impelled into said siphon near the discharge end thereof.
  3. In combination with a siphon having

a source of supply and a place of discharge, an air pump whereby said siphon may be primed and maintained free of air, a force pump drawing water from said source of supply, and a discharge pipe from said force pump entering said siphon near the discharge end thereof whereby a flow of liquid may be maintained through the discharge end of said siphon.

4. In combination with a siphon having a source of supply and place of discharge, an air pump whereby said siphon may be primed and maintained free of air, a force pump drawing water from said source of supply, a discharge pipe from said force pump entering said siphon near the discharge end thereof, and an ejector nozzle attached to said pipe and inside of said siphon whereby liquid may be impelled into the discharge leg of said siphon.

5. In combination with a siphon having a source of supply and place of discharge, a check valve at the discharge end thereof, an air pump to draw air from said siphon, a force pump drawing water from said source of supply, a discharge pipe from said force pump entering said siphon near the discharge end thereof, and an ejector nozzle attached to said pipe and inside of said siphon whereby liquid may be impelled into the discharge leg of said siphon.

In witness whereof we have signed our names to this specification.

CARROLL H. CASE.
WILLIAM C. FARRAR.
